UNITED STATES PATENT OFFICE.

WILLIAM SICKINGER, OF CHICAGO, ILLINOIS.

ELECTRICALLY-HEATED WAFFLE IRON.

Application filed July 21, 1921. Serial No. 486,478.

To all whom it may concern:

Be it known that I, WILLIAM SICKINGER, a citizen of the United States, residing at Chicago, in the county of Cook and State of Illinois, have invented certain new and useful Improvements in Electrically-Heated Waffle Irons, of which the following is a specification.

This invention relates to waffle irons in which a pair of complementary grids between which the batter is introduced to produce the waffle are backed up by electrical resistance adapted to heat the grids to cooking temperature.

The object of the invention is to improve the construction of a device of this kind in a manner to make it more effective and durable in use and cheap to produce, particularly in the element of labor required for assembling the parts.

One feature of the invention consists in subdividing the housing of the utensil in a middle plane so as to provide a pair of box-like containers, introducing into these containers first the heat insulating medium preferably with an electrically non-conducting and high refractory facing, then the electric resistances in flat sheet-like form, then a layer of electrically non-conducting but heat conducting and refractory cloth in direct contact with the electrical resistances, and then the grid in direct contact with said non-conducting cloth so as to receive the heat directly therefrom; the grid being fitted to the box-like half of the housing in a manner to completely fill the same and tightly confine the laminated structure built up of the parts enumerated as lying beneath it.

Another feature of the invention consists in the particular construction of hinges employed for connecting the two housing sections in a manner to not only permit them to swing to open and closed positions but to separate by bodily movement perpendicular to their dividing plane; the two sections of the utensil being provided with handles, one of which is particularly adapted for holding down the lower or base section, while the other is adapted to be gripped in a manner to lift the other section bodily as distinguished from merely swinging its free side upward upon its hinges.

Still another feature of the invention resides in the construction of the connecting means for the resistances whereby flat re-

sistance elements introduced in units as coils upon flat cores may be united in series without objectionably adding to the thickness of the laminæ of resistance elements. 60

In the accompanying drawings—

Figure 1 is a vertical transverse section of a utensil embodying the several features of the invention.

Figure 2 is a plan view of the base section with the greater portion of the grid removed to disclose the resistance elements beneath it.

Figure 3 is a vertical section in a plane indicated by the line 3—3 of Figure 2.

Figure 4 is a detail view of the hinge 70 which permits bodily lifting of the upper section; and

Figures 5 and 6 are sectional views in planes at right angles to each other of the flat connector for the resistance elements. 75

1^a and 1^b represent two halves of the shell or housing and 2 represents hinges for connecting the same. The hinges involve the peculiarity of permitting vertical bodily movement of the upper housing by having 80 one of the plates 2^a thereof secured with freedom of vertical motion by a keeper 2^b, the vertical motion being limited by an outward flange 2^c.

Within the shells 1^a and 1^b are located, 85 first, one or more laminæ of heat insulating and preferably non-combustible material 3, for instance sheets of asbestos, and upon these sheets are preferably laid a facing 4 of mica or other material of high heat resistance; next is located a layer 5 of resistance elements which are preferably subdivided into a plurality of units, such as 5^a, 5^b, and 5^c, each consisting of a flat core 5^d of refractory material, and a tape like resistance conductor 5^e arranged in flat coils thereon. Conductors 5^e may be hitched through perforations in the core 5^d as shown at 5^f, and the units are connected in series by means of clips 6 which are made by cutting tongues 6^a in the metal sheet 6^b and leaving the free ends of the conductors 5^e alternately above and beneath said tongues, with the conductor ends to be connected overlapped so that they are pressed in firm 95 contact one with the other.

While the material of the connecting clips is preferably of electrically conducting character, this is not essential if the ends are overlapped and held snugly one upon the 100 other.

The base section 1^b is supported on hollow

- posts 7 from a heat screen 8 which is in turn suspended by feet 9 above the table or other surface upon which the utensil is intended to rest.
3. A handle 10 for holding down the base section and a grip handle 11 for manipulating the upper section are provided, and these handles are adapted not only to effect opening and closing movement upon the 10 unit 2, but to bodily lift the upper section relatively to the lower section if desired.
- I claim:
1. An electrically heated cooking utensil comprising a box-like housing, an insulating lamina therein, a resistance lamina overlying said insulating lamina, and a cooking grid overlying and in close proximity to the resistance lamina; the grid fitting the housing snugly and holding in contact relation 20 the laminae located beneath it.
  2. In an electrically heated cooking utensil, a box-like housing, an insulating lamina in said housing, a resistance lamina lying upon said insulating lamina, an electric non-conducting but heat conducting refractory lamina overlying said resistance lamina, and a cooking grid snugly fitting the housing, lying upon the refractory laminae and holding all of said lamina in compression.
  3. In an electric waffle iron, a pair of box-like housings containing grids and resistances in heating relation to said grids; said housings having a connecting hinge comprising a plate through which the hinge is connected to one of the housings, a keeper 35 connected to said housings and overlying the plate while permitting it to slide vertically therein, and a limiting projection on the plate for engaging said keeper at the end of the sliding movement.
  4. In an electric cooking utensil, the combination of laminated insulating and heating elements, and a connector for two heating elements comprising a flat metal clip slotted to provide tongues relatively displaceable above and below the plane of the clip, and flat metal terminals projecting from the heating elements and interwoven between said tongues.
  5. In an electric cooking utensil, the combination of laminated insulating and heating elements, and a connector for two heating elements comprising a flat metal clip slotted to provide tongues relatively displaceable above and below the plane of the clip, and flat metal terminals projecting from the heating elements, interwoven between said tongues and lapped upon the other.
  6. In an electric cooking utensil, a cooking grid, a housing containing the same together with the heating resistance therefor, a heat screen having means for spacing it from a surface upon which it stands, and hollow pillars supporting the housing of the grid in spaced relation to said heat screen.

Signed at Chicago, Illinois, this 16th day of July, 1921.

WILLIAM SICKINGER.
